THERMAL INSULATING JACKET

Joseph T. Kamowski, Nanticoke, Pa.

Application September 21, 1943, Serial No. 503,273

2 Claims. (Cl. 154—44)

This invention relates to thermal insulation and more particularly to jackets and covers for conserving the heat in hot water storage receptacles, such as hot water tanks.

Considerable heat is dissipated from hot water storage tanks without any beneficial results. In fact, the lost heat, particularly in the warm seasons, adds to the heat of a room and, sometimes, damages nearby woodwork, wall surfaces and the like.

An important object of the invention is to provide an easily applied and removed heat-insulating cover or jacket for conventional hot water storage tanks.

Another object is to provide a cover for the purpose mentioned, which will insulate not only the sides of the tank, but the top and bottom portions as well.

Still another object is to provide a cover, as last described, which is not permanently attached to the tank, but which will not sag under its own weight.

Other objects and advantages of this invention will be apparent during the course of the following detailed description of the invention, taken in connection with the accompanying drawing, forming a part of this specification, and in which drawing:

Figure 1 is a perspective view, showing the novel cover applied to a hot water tank.

Figure 2 is an elevation of the side wall cover portion, spread out.

Figure 3 is a horizontal section, substantially upon the line 3—3 of Figure 2.

Figure 4 is a horizontal section through a tank and the side wall cover portion applied thereto.

Figure 5 is a top plan of the two sections making up the top cover portion.

Figure 6 is a bottom plan of the two sections making up the bottom cover portion.

Figure 7 is a view; similar to Figure 6 but with the two sections united.

Figure 8 is a fragmentary vertical section of the side wall cover portion.

Figure 9 is a fragmentary vertical section of the side wall and top cover portions applied to a tank.

In the drawing, wherein for the purpose of illustration is shown a preferred embodiment of the invention, and wherein similar reference characters designate corresponding parts throughout the several views, the letter A may designate the novel cover or jacket as a whole, the letter B the side wall portion thereof, C the top wall portion, D the bottom wall portion, and E a conventional hot water storage tank.

The side wall portion B of the novel cover A may be constructed of a sheet 10 of canvas or other suitable pliable material, and coated or impregnated, if desired, with mildew-inhibiting and/or fireproofing materials. It is preferably of one piece construction and adapted to extend wholly around the side of the tank, being longer than the length of the outer circumference of the tank, to accommodate for heat insulating material carried by it, and being higher than the height of the tank, also because of insulating material which preferably projects above and below the horizontal planes of the tank ends, as will be more fully explained. In order to easily 5 secure and remove the side wall portion B to and from the tank E, it is preferred to employ so-called zippers along the vertical ends 11 and 12 of the portion B.

Extending from the top and bottom ends of the 10 main part 13 of the portion A, are a plurality of flaps 14 and 15, truncated conical in general shape, with the smaller ends of flaps 14 formed into hems 15' through which extend a cord 16, or the like. The smaller ends of flaps 15 are 15 similarly provided with hems and a draw-string or cord 16, as shown in Figure 2. The function 20 of this means will be explained later.

Carried by the portion A (exclusive of the flaps 13 and 14) is suitable heat insulating material 30 17, as so-called rock wool disposed within the spaces between the sheet 10 and an inner sheet 18 which may be of any suitable pliable material. The material of the sheet 18, may be formed into loops 19 as in Figure 2 and sewn longitudinally to the sheet 10, so that a plurality of pockets 25 20 will be formed in which the insulating material 17 may be placed. The ends of the pockets 35 may be closed as by securing the upper and lower ends of the sheet 18 to the sheet 10, such as at 21.

40 Since most hot water storage tanks have a conduit (or sometimes two) extending outwardly from the side wall, the sheet 10 must be provided with a suitable opening or openings therefor. Such opening comprises a pair of semi-circular cut outs, or recesses 22, one in each of the vertical ends 11 and 12 for each conduit. Of course, this entails the use of several runs of 45 zippers, as is obvious.

50 The top wall portion C comprises two semi-circular sections 25 and 26, as shown in Figure 5. Each section has preferably a top wall 27, bottom wall 28, curved outer wall 29 and flat inner wall 30. These walls may be of canvas or some 55 of them may be of plywood, as desired, but the several walls are suitably secured together to

form a pocket 31 containing suitable heat-insulating material 32.

Radially-extending reinforcing ribs 33 may be provided to brace the sections 25 and 26 and semi-circular recesses 34 and 35, provided in their flat inner walls 30 to accommodate the usual conduits extending from the top of the ordinary hot water storage tank. Of course, the two sections 25 and 26 when arranged with their flat inner walls 30 in abutment, constitutes a flat cylinder with an outer circumference substantially similar to that of the tank E.

The bottom wall portion D is somewhat like the portion C, but may be thinner and not be provided with ribs. Since but one conduit usually extends from the bottom of the tank E, there is but one semi-circular recess 40 in each section 41 and 42 of the portion D. In order to attach the two sections 41 and 42 together to form a flat cylinder, suitable hook and eye means 43 may be provided on the outer (lowermost) faces 44 of the sections 41 and 42. Where legs extend from the lower face of the bottom wall of a tank, the sections 41 and 42 may be slotted as at 45 to accommodate such legs.

The hot water storage tank E is shown as having a cylindrical side wall 50, top or end wall 51 and bottom or end wall 52 with a conduit 53 extending outwardly from the side wall 50, two conduits 54 and 55 from the top wall 51 and one conduit 56 from the bottom wall 52. Three legs 57 (the conventional number) are shown as supporting the tank.

In assembling the novel cover or jacket A, the top wall portion C is first placed in position upon the top wall 51 of the tank and then the side wall portion B placed in position, so that the cut-outs or recesses 22 accommodated the conduit 53 and the flaps 14 at the upper end thereof, being pliable and free of heat insulating material, may be disposed upon the portion C whereupon the drawstring 16 may be manipulated so as to draw the flaps 14 together, with the drawstring 16, encircling the conduits 54 and 55, and the ends of the drawstring 16 firmly tied and tucked under the flaps 14.

Next, the bottom wall portion D may be positioned to cover the bottom wall 52 of the tank E and when the hook and eye means 43 is employed, the two sections 41 and 42 will be held together, encircling the conduit 56 and held frictionally thereto. The three flaps 15 may now be positioned to accommodate the three legs 57 and then carried under the tank E and portion D whereupon the drawstring 16 thereof manipu-

lated to draw the flaps 15 together and the drawstring then tied and tucked under the flaps as explained. The drawstring 16, of course, encircles the conduit 56.

5 The greater portion of the weight of the portion B is upon the portion C, but the latter is reinforced by its walls and ribs, and the drawstrings 16 and hems 15 maintain the flaps 14 and 15 taut over the portions C and D, so that a 10 neat, trim appearance is provided.

From Figure 9 it will be seen that the heat insulating material 17 extends upwardly beyond the horizontal plane of the upper face of the top wall 51 of the tank E, so that there is complete insulation coverage of the tank at the junction of the top or end wall 51 and side wall 50.

When the portion B is disposed about a tank E, it will appear, in horizontal cross section substantially as in Figure 4.

20 Various changes may be made to the form of the invention herein shown and described without departing from the spirit of the invention or scope of the claims.

What is claimed is:

25 1. In a heat-insulating jacket for a hot water storage tank having a conduit extending from an end thereof, a side wall portion having end flaps, with heat insulating material over the inner face of said side wall portion, said flaps being free of 30 said heat-insulating material, an end wall portion, comprising two sections extending about that part of said conduit nearest said tank and also extending to the inner face of said side wall portion, said end wall portion being provided with 35 heat insulating material, said flaps extending over a portion of the outer face of said end wall portion toward said conduit, and means for drawing said flaps together and maintaining them taut over said part, said means encircling said 40 conduit, and comprising a drawstring extending through the free ends of said flaps.

2. In a heat-insulating jacket for a hot water storage tank having a side wall, an upper end wall and a conduit extending from said upper 45 end wall, a side wall portion embracing the side wall of said tank, provided with heat-insulating material disposed over the surface of said side wall portion, and truncated conical shaped end flaps extending over a part of said upper end 50 wall adjacent the edges thereof, and means for maintaining said flaps taut over said part, said means encircling said conduit, and comprising a drawstring slidably extending through the free, narrower ends of said flaps.

55 JOSEPH T. KAMOWSKI.
